INVENTOR:
Jacob Springer

United States Patent Office.

JACOB SPRINGER, OF LANCASTER, PENNSYLVANIA, ASSIGNOR TO HIMSELF,
A. C. FLINN, AND H. B. McNEAL, OF SAME PLACE.

Letters Patent No. 77,671, dated May 5, 1868.

IMPROVED APPARATUS FOR RECTIFYING SPIRITS.

The Schedule referred to in these Letters Patent and making part of the same,

TO ALL WHOM IT MAY CONCERN:

Be it known that I, JACOB SPRINGER, of the city of Lancaster, and State of Pennsylvania, have invented a new and useful Improvement in Tubs for Doubling or Rectifying Spirits in Distilleries, and I do hereby declare that the following is a full, clear, and exact description of the construction and operation of the same, reference being had to the accompanying drawings, making a part of this specification, in which the connecting-pipes, with the still, § I, and the cooler or condensing-tub, § III, is shown. § II, situated between the two, shows my improvements in place.

The nature of my invention consists in providing my tub with three chambers, and means for heating the singlings before charging the lower chambers, so as not seriously, if at all, to check the continuous process of evaporation, and thereby save much in time and one-third the fuel usually expended in the use of the single-chambered vessel in universal use.

To enable others skilled in the art to make and use my invention, it is not necessary for me to describe the operation of mashing, mixing the worts or wash, and process of distillation, as my improvement consists in the construction of the vessel § II, which I call the doubler or doubling-tub, divided into three chambers, D E F. The dotted lines indicate the tube from the pump, by which the singlings or low-wines are put in the upper chamber, F. This has a copper dome, H, which is heated from the swan's-neck, G, and steam in the middle chamber, E.

The conducting-pipe, 13, from chamber E through F, is surrounded by a jacket or cylinder, to separate the colder contents or singlings in F, to prevent condensation in the pipe. This chamber F being charged and heated to near the boiling-point, is ready to charge the lower chambers, E D, successively, by means of tubes 12, 11, and slide-valves S V. I also use the air-valves A V, to guard against a collapse, and man-holes, M, to facilitate cleaning out the lower and middle chambers, D E, in which appliances I claim no novelty.

To provide an outlet, in case the contents in the upper chamber should come to a full boiling-heat, I have a pipe, 6, that conveys any vapor formed, over into the beer, in the chamber C of the still § I. This prevents any waste of material.

The use of the connecting-pipes 9, 10, and 13 is well understood, and common. But I am not aware that a dome, H, or its equivalent, for heating an upper chamber in the doubling-tub was ever before used in the manner shown. It (the doubler) also answers the purpose of concentrating the spirits from the still, as well as from the singlings, as they mingle, through the medium of the connecting-pipes from one to the other, in the general combination. This upper chamber for heating the singlings before charging not only saves time and fuel, but has other advantages, for when the singlings are conveyed from the pump to the bottom of a single-chambered tub, there is a great tendency to clog the pipes by the mixed wash being blown into them.

When all the points are duly considered, and compared with the old process, they will be found to present highly-important features of improvement, the adoption of which will be a great saving, and produce the most satisfactory results.

What I claim as my invention, and desire to secure by Letters Patent, is—

The construction and arrangement of the doubling-tub, with its three chambers, D E F, copper or metallic heating-dome H, or its equivalent, in combination with the pipes 5, 6, 11, and 12, arranged substantially in the manner and for the purpose specified.

JACOB SPRINGER.
